(57) **CLAIM**

The ornamental design for a carabiner, as shown.

DESCRIPTION

FIG. 1 is a perspective view of a carabiner showing my new design;

FIG. 2 is a bottom, front, right side perspective view thereof;

FIG. 3 is a top, rear, left side perspective view thereof;

FIG. 4 is a front elevational view thereof, the rear elevational view being a mirror image;

FIG. 5 is a right side elevational view thereof;

FIG. 6 is a left side elevational view thereof;

FIG. 7 is a top plan view thereof; and,

FIG. 8 is a bottom plan view thereof.

The broken lines depict an environment of use and form no part of the claim.
